UNITED STATES PATENT OFFICE

JOHN STAMM IRWIN, OF JACKSON HEIGHTS, NEW YORK

COMBINATION READING DESK AND BOOKCASE

Application filed February 17, 1931. Serial No. 516,347.

This invention relates to a combination bookcase and reading table.

An object of the invention is to provide a simple, efficient, strong and artistic-looking device which is supportable, not too heavy, and will take up a minimum of floor space when not in use.

A further object is to provide such a device provided with an extension shelf to support a plurality of books thereon, capable of extending in front of a chair or lounge or similar seat, while the bookcase is disposed adjacent the reader.

A further object is to provide simple and efficient means whereby the shelf may be disposed to extend in different directions from the bookcase.

A still further object is to provide simple and efficient means whereby the reading shelf or table can be readily removed from the bookcase and supported therefrom, out of sight, when not in use.

Further and more specific objects, features and advantages will more clearly appear from a consideration of the specifications herein-after taken in connection with the accompanying drawing which forms part of the specification and which illustrates a present preferred form of the invention.

In brief and general terms the invention is designed for the use of students or readers who desire to sit comfortably in a chair or recline in a sitting position on a couch or lounge with a bookcase closely adjacent them and with the books to be studied spread out of a convenient shelf or table in front of them, thus having the bookcase handy for reference to other books and having the books being read supported in front of them without requiring the reader to hold the books. This is especially useful when a student or reader is desirous of having several books spread out in front of him for comparison or joint reference.

The bookcase proper, is of any suitable de-

sign, preferably not occupying much floor space and being provided with a plurality of compartments for books, periodicals and newspapers. The bookcase is preferably greater in height than in length. The top of the bookcase may be of any desired shape, but is preferably provided with spaced notched portions with inclined surfaces acting as a supporting surface for a shelf or table to be disposed thereon. The shelf is in width equal to the length of the inclined surfaces on the top of the bookcase, but in length is several times the length of the bookcase and of sufficient dimensions to support several books thereon, when the books are open in front of the reader. The bookcase on each side is provided with cooperating fastening elements so that either end of the shelf may be fastened to the corresponding elements on the bookcase to hold the shelf in place and permitting the major portion of it to extend laterally from the bookcase in one direction or the other, depending upon whether the reader requires the bookcase to be disposed to his right or left. Preferably the shelf or table element is provided with a bevelled cleat or similar supporting element extending transversely through the rear face. This supporting element is adapted to cooperate and engage with a similar element on the back wall 10a of the bookcase so that when the shelf is removed from its operative position it can be hung in back of the bookcase. The length of the shelf and the height of the bookcase are so related that when the shelf is thus supported in the back thereof, it will be out of sight.

Thus the bookcase being of relatively light-weight and not of greater length can be readily picked up and carried to any desired position, preferably being disposed along a wall, out of the way, when not in use. When it is desired to use it, it is moved adjacent one side or the other of a chair or lounge and the shelf is then fastened in position.

across the top of the bookcase to extend laterally therefrom in a desired direction over in front of a chair or lounge so that books may be disposed on the table element or shelf, at hand to the reader.

6 The invention is illustrated in the drawing, of which:

Fig. 1 is a front elevation of the invention with the shelf in place;

10 Fig. 2 is a side elevation thereof;

Fig. 3 is a rear elevation thereof; and

15 Fig. 4 is a side elevation of the shelf as it is disposed when hung on the back of the bookcase.

15 The present preferred form of the invention comprises a bookcase having side walls 10 and 11, spaced apart by shelf elements 12, 13 and 14, providing compartments A and B, for books, periodicals, newspapers, and the like. Preferably the upper compartment A is used for books and the lower compartment B for magazines and larger periodicals. The height of the bookcase is considerably greater than the length between walls 10 and 11. It 20 will be noticed that the top portion of the wall members 10 and 11 are provided with a notch 15 and rearwardly inclined surfaces 16. This notch portion together with the rearwardly inclined surface forms a support 25 for a shelf 17. This shelf preferably having bottom and lateral flanges 18 and 19. The shelf 17 is preferably two or three times as long as the bookcase. The ends of the shelf are provided with hook elements 20 which 30 are adapted to engage respectively with corresponding eye portions 21 which are disposed on the outside of the walls 11 and 10 near the notch portions 15. In this manner the shelf 17 can be disposed on top of the bookcase and fastened to extend laterally 35 therefrom in one direction or the other, as shown in Fig. 1. On this shelf one or more books may be spread out for study and examination at the same time.

40 This laterally extending shelf on the top of the bookcase will permit the reader to sit in a chair or in a reclining position on a lounge and study, while having a portable bookcase disposed adjacent him for ready reference. After the reader is finished the books are restored to their proper shelf, and the hook 20 is released and the shelf 17 can be 45 removed from the top of the bookcase. The shelf at its rear surface is provided with a bevelled cleat 22 adapted to cooperate with a similar bevelled cleat on the back 10a of the bookcase as shown in Fig. 3. This cooperation will permit the shelf to be supported in back of the bookcase when not in use, and 50 thus dispose it compactly ready for use, out of sight, especially when the bookcase is moved to a position along a wall, out of the way.

55 It will thus be seen that the invention affords a simple, compact, strong combination

bookcase and reading table readily portable to any position adjacent a lounge or chair with the books available for ready reference, and those in use disposed handily on the shelf in front of the reader. The table element or shelf can be quickly placed in position or removed therefrom and when not in use can be disposed out of sight on the back of the bookcase, and the bookcase moved to a convenient position out of the way.

70 75

While the invention has been described in detail and with respect to a present preferred form thereof it is not to be limited to such details and forms since many changes and modifications may be made in the invention without departing from the spirit and scope of the invention in its broadest aspects. Hence it is desired to cover any and all forms and modifications of the invention which may come within the language or scope of any one or more of the appended claims.

80 85

What is claimed is:

1. A combination reading desk and bookcase which comprises a bookcase unit, a shelf detachably disposed thereon, bevelled cleats on the back of the shelf and the unit to engage and support the shelf vertically in back of and from the unit when not in use.

90

2. A combination reading desk and bookcase which comprises a bookcase unit having notched portions at the top thereof forming rearwardly and upwardly inclined surfaces, a shelf disposable in said notched portions and against said surfaces and of a length to extend laterally from the unit over a chair or lounge.

95 100

3. A combination reading desk and bookcase which comprises a bookcase unit having notched portions at the top thereof forming rearwardly and upwardly inclined surfaces, a shelf disposable in said notched portions and against said surfaces and of a length to extend laterally from the unit over a chair or lounge, and means on the unit and shelf to cooperatively engage to hold the shelf in position on the top of the unit.

105 110

4. A combination reading desk and bookcase which comprises a bookcase unit having notched portions at the top thereof forming rearwardly and upwardly inclined surfaces, a shelf disposable in said notched portions and against said surfaces and of a length to extend laterally from the unit over a chair or lounge, and means on the unit and shelf to cooperatively engage to hold the shelf in position on the top of the unit, and means on each side of the unit and each end of the shelf to respectively engage to hold the shelf in position to extend laterally from the unit in one direction or opposite.

115 120 125

5. A combination reading desk and bookcase which comprises a bookcase unit, the upper portion of which is provided with a notch portion forming rearwardly and upwardly inclined surfaces, a fastening element

130

on each side of the unit adjacent the notched portion, a flanged shelf disposable in said notched portion, and means on each end of the shelf to engage the respective fastening elements on the unit to hold the shelf in position to extend laterally from the unit in either direction.

Signed at Jackson Heights, N. Y., in the county of Queens and State of New York
10 this 13th day of February, A. D. 1931.

JOHN STAMM IRWIN.
